UNITED STATES PATENT OFFICE.

OSCAR H. BROWN, OF EASTPORT, MAINE.

VEST-HOLDER.

No. 874,738.

Specification of Letters Patent.

Patented Dec. 24, 1907.

Application filed July 2, 1907. Serial No. 331,862.

To all whom it may concern:

Be it known that I, OSCAR H. BROWN, a citizen of the United States of America, residing at Eastport, in the county of Washington and State of Maine, have invented new and useful Improvements in Vest-Holders, of which the following is a specification.

This invention relates to vest holders, and the principal object of the same is to provide a device of simple construction which will hold the vest at the back of the neck of the wearer above the lower edge of the collar.

Much annoyance is caused by the upper edge of the vest at the back of the neck getting underneath the lower edge of the collar, and binding at this point. With comparatively high shirt collars such as are worn today, the lower edge of the collar is liable to ride over the top edge of the vest and become very troublesome and annoying. It is to overcome this annoyance, and to provide a simple device for holding the upper edge of the vest in proper relative position to the shirt collar that I have devised the construction shown in the accompanying drawings, in which:

Figure 1 is a sectional view through the shirt collar, the neck band and a vest at the back, and showing my vest holder in operative position. Fig. 2 is a face view of my vest holder. Fig. 3 is a similar view of the opposite side thereof. Fig. 4 is a side view similar to that shown in Fig. 2 with the sliding member of the clasp in a disengaging position. Fig. 5 is a transverse sectional view. Fig. 6 is a longitudinal sectional view of the holder.

Referring to the accompanying drawing for a more particular description of my invention, the numeral 1, Fig. 1, designates an ordinary shirt collar of the turn-down style, 2 is the neck-band of the shirt to which the collar is attached by means of the rear collar button 3, and 4 is the upper rear neck portion of the vest.

My device may be used with any style of collar. The vest holder comprises a plate *a* having an aperture *b* therein to engage the shank of the button 3, said aperture being of a size sufficient to readily pass over the head of the button and engage the shank thereof.

On the opposite end of the plate *a* to the opening *b* a pair of upwardly extending prongs *c* are provided. A sliding member *d* is provided with flanges *e* which are bent over the plate *a* and at the lower edge of said sliding member *d* an inclined prong *f* is provided. Secured to the holder or plate *a* is a spring latch *g* having an angular toe *h* which projects through an opening *i* in the holder *a*, said latch being connected to the holder *a* by means of a pin or rivet *j*.

The operation of my invention may be briefly described as follows: The prongs *c* are engaged with the material of the vest at the inside near the upper edge of the rear neck portion thereof, as shown in Fig. 1, and the sliding member *d* is pushed down until the prong *f* enters the material between the prongs *c*, and the toe *h* of the latch *g* is sprung over the top edge of the slide *d*. The shank of the collar button 3 is then engaged by the aperture *b* in the holder *a*, thus holding the vest at the required height to prevent the same from riding under the collar.

From the foregoing it will be obvious that my vest holder may be connected to the vest at any desired point below the upper edge of the vest to hold the upper edge at the required point relatively to the collar. In removing the vest the holder is detached from the collar button, and the holder permitted to remain connected to the vest.

Having thus described the invention, what I claim is:

1. A vest holder comprising a stationary plate having an aperture therein to engage the rear collar button, upwardly extending prongs upon the lower end of said plate, a sliding member provided with a prong adapted to engage the material between the prongs on the plate, and a spring latch for holding said sliding member in operative position, substantially as described.

2. A vest holder comprising a member adapted to engage a collar button, a sliding member mounted on said first mentioned member and provided with a prong, and a spring latch for holding said sliding member in operative position.

3. A vest holder comprising a stationary member and a sliding member mounted

thereon, prongs on said members, a spring latch secured to the stationary member and provided with an angular toe normally extending through an opening in said stationary member to engage the sliding member and prevent its movement upon the stationary member.

In testimony whereof, I affix my signature in presence of two witnesses.

OSCAR H. BROWN.
